US0D1041893S

(12) **United States Design Patent** (10) **Patent No.:** **US D1,041,893 S**
(45) **Date of Patent:** **** Sep. 17, 2024**

(54) **EARPHONE BOX**

(71) Applicant: **Shenzhen Earfun Technology Co., Ltd.**, Shenzhen (CN)

(72) Inventor: **Meiling Liu**, Shenzhen (CN)

(73) Assignee: **Shenzhen Earfun Technology Co., Ltd.**, Shenzhen (CN)

(**) Term: **15 Years**

(21) Appl. No.: **29/885,526**

(22) Filed: **Feb. 24, 2023**

(30) **Foreign Application Priority Data**

Aug. 26, 2022 (CN) 202230561809.7

(51) **LOC (14) Cl.** **03-01**

(52) **U.S. Cl.**

USPC **D3/294**; D13/108

(58) **Field of Classification Search**

(57) **CLAIM**

The ornamental design for an earphone box, as shown and described.

DESCRIPTION

FIG. 1 is a front perspective view of a earphone box showing my design.

FIG. 2 is a rear perspective view of the earphone box in FIG. 1.

FIG. 3 is a front elevation view of the earphone box in FIG. 1.

FIG. 4 is a rear elevation view of the earphone box in FIG. 1.

FIG. 5 is a left side elevation view of the earphone box in FIG. 1.

FIG. 6 is a right side elevation view of the earphone box in FIG. 1.

FIG. 7 is a top plan view of the earphone box in FIG. 1.

FIG. 8 is a bottom plan view of the earphone box in FIG. 1; and,

FIG. 9 is a front perspective view of the earphone box showing my design and the earphone box in an open position.

The broken lines depict portions of the earphone box that form no part of the claimed design.

1 Claim, 9 Drawing Sheets
